ATTORNEY

UNITED STATES PATENT OFFICE.

PAUL E. DEMMER, OF MARYSVILLE, CALIFORNIA, ASSIGNOR, BY DIRECT AND MESNE ASSIGNMENTS, TO D. & W. SPECIALTY COMPANY, OF MARYSVILLE, CALIFORNIA, A CORPORATION.

TIMER.

Application filed April 3, 1922. Serial No. 548,903.

To all whom it may concern:

Be it known that I, PAUL E. DEMMER, a citizen of the United States, residing at Marysville, county of Yuba, State of California, have invented certain new and useful Improvements in Timers; and I do declare the following to be a full, clear, and exact description of the invention, reference being had to the accompanying drawings, and to the characters of reference marked thereon, which form a part of this application.

This invention relates to improvements in timers for use particularly on Ford cars, the principal objects being to produce a timer which may be readily installed in place of the one provided as regular equipment without necessitating any structural or other changes being made to the engine or other parts; which is so constructed that "arcing" is eliminated, thereby saving the contact strips and brushes from wear; and the troublesome coil-vibrators with which Ford systems are equipped may be rendered inactive when the batteries are used without interfering with the intensity of the spark, and the original uncertain ignition system is converted into a positive make-and-break system.

A further object is to construct a timer for the above named purpose which will have a single breaker-point mechanism to control the passage of the current through the distributor rings which may be readily adjusted when necessary without removing the timer and which is within easy access of the operator and visible while any such adjustment is being made.

Another object is to provide a timer so constructed that "missing" of a spark is eliminated, and the device as a whole will give good service without repairs or replacements for a long period of time.

These objects I accomplish by means of such structure and relative arrangement of parts as will fully appear by a perusal of the following specification and claims.

In the drawings similar characters of reference indicate corresponding parts in the several views:

Fig. 1 is a front view of the timer assembled, with the removable section of the cover removed to show the accessibility of the adjustable breaker-point mechanism.

Fig. 2 is a similar view with the cover entirely removed. 55

Fig. 3 is a cross section on the line 3—3 of Fig. 1.

Fig. 4 is a detached section assembly of a brush and cam unit, mounted on the cam-shaft. 60

Fig. 5 is a fragmentary cross section of the timer taken on the line 5—5 of Fig. 2.

Fig. 6 is a detached view of one of the segmental distributor rings and its binding-post pin. 65

Fig. 7 is a perspective view of a detachable cover-segment.

Referring now more particularly to the characters of reference on the drawings, the numeral 1 denotes a circular casing, provided near its outer or front end with a centrally orificed partition or wall 2. 70

Turnably fitted on to the front end of the casing is a cover 3, centrally cupped out as 75 at 4 so that it may be held in place by the usual clamp member provided for this purpose on all Ford cars (not shown).

This cover is partially cut away from its outer periphery toward the center as shown at 5, this cut away portion being normally filled by a removable cover segment 6, which may be detachably connected to the casing and to the main cover member by any suitable clip or other holding means, such as 80 85 is indicated in the drawings.

Mounted on the outer face of the wall 2 and insulated therefrom is a plate 7 having a fixed contact member 7^a, connected to a condenser 8 of standard form located at any suitable point, while co-operating with said contact is another contact 9 mounted on a movable arm 10 pivoted onto the wall 2 and held by spring means 11 so that the contacts normally engage, the arm 10 and casing being grounded, as is the magneto of the system and the condenser, so that all these members are in a common circuit. 90

Seated in the casing 1 on the opposite or inner side thereof from the wall 2 is a ring 12 of insulation material embedded flush in which is a continuous metal collecting ring 13, and spaced therefrom a plurality of segmental distributing rings 14, preferably four (one for each cylinder of the engine) and spaced from each other, the insulation material of the ring 12 projecting therebetween. To each ring 14 is fixed a 100 105

pin 15 which projects beyond the casing 1 to serve as a means of connecting the usual wires leading to the coils of the ignition system.

5 The insulation ring 12, on each side of the pins 15 and for the full width of said ring projects through the casing in the form of radial ribs as shown at 16, the casing being slotted to receive these ribs. In this manner not only are the pins well insulated from the casing, but the insulation ring is positively prevented from turning therein.

10 The collecting ring 13 is connected in circuit with the plate 7, and the condenser, by a wire 17 or other suitable means, so long as no contact with the casing is made.

15 The cam shaft 18 of the engine projects through the casing from the inner end and through the wall 2, terminating short of the 20 face of the cover 3.

20 Fitted onto said shaft is a sleeve 19 on which is fixed an insulation arm 20 in the outer face of which a conducting brush member 21 is slidably mounted and adapted 25 to engage the rings 13 and 14 in common. The brush is forced into constant frictional engagement by spring means 22 acting thereon and seated in the arm 20.

25 Mounted on the shaft in fixed relation 30 with respect to the arm 20 is a circular cam 23, having a plurality of notches or recesses 24 in its outer face, the number of such recesses being the same as the number of segmental distributing rings 14. The breaker- 35 arm 10 is provided with a lug 25 on its face adjacent the cam and is positioned to ride on the circular face thereof, at which time the arm will be raised and the contacts 7^a and 9 broken.

40 When with the rotation of the cam the recesses 24 move across the lug 25, the latter drops thereinto, and the contacts are closed owing to the pressure exerted on the arm 10 by the spring 11.

45 The time of contact of the breaker points is less than the time of contact of the brush with the distributor rings, and takes place while the brush is intermediate the ends of any of such rings, so that the brush contacts with a ring before the circuit is closed, and the latter is again opened before the brush leaves the ring. This important feature, as will be evident, positively eliminates "arcing" or jumping of the current between 50 the metal surfaces when separated, which causes the burning of the conductors—a cause of deterioration far greater than actual wear, which is negligible in comparison.

55 60 The brush-arm and cam are mounted and held on the shaft in a definite fixed relation by the following means: The sleeve 19 projects beyond the arm 20 toward the cam, and is slotted at such end as at 26 to receive the 65 central enlargement 27 of a pin 28, one end

of which is seated in the shaft 18 while the other end projects into a groove 29, narrower than the groove 26, cut in the adjacent end of the cam, which slips over the grooved end of the sleeve 19.

70 It will thus be seen that when once placed together in the sequence named, neither the arm nor the cam can have rotative movement relative to each other or to the shaft, while at the same time the pin can never fall out. At the same time it is a very simple matter to assemble or dismount the parts when necessary.

75 The cam is held from movement outwardly of the shaft by a lock nut 30 screwed on the end of said shaft.

80 The value of functioning of a condenser in ignition apparatus is well known and needs no explanation. By reason of the use of such a device in a Ford timer, the coil 85 vibrators may be screwed down as their use is no longer imperative. If desired however, the condenser may be omitted, in which case the current will flow direct to the collecting rings, and the use of the vibrators must 90 be continued.

85 In either case the current flows to the common collector rings and is there passed to the various coils through the distributor rings by reason of the common brush 21, 95 the time and length of such distribution being governed by the making and breaking of the breaker points or contacts 7^a and 9.

90 By reason of the segmental cover, the latter may be turned to the position shown in 100 Fig. 1 without disturbing the clamp or holding means, when the breaker points will be fully exposed, and may be then inspected or adjusted without removing the timer or any part thereof from its place.

105 The auxiliary cover member 6 may then be replaced, and the cover as a whole turned to bring the cut away portion underneath, so as to remove the possibility of dust and dirt sifting into the interior.

110 From the foregoing description it will be readily seen that I have produced such a device as substantially fulfills the objects of the invention as set forth herein.

115 While this specification sets forth in detail the present and preferred construction of the device, still in practice such deviations from such detail may be resorted to as do not form a departure from the spirit of the invention, as defined by the appended 120 claims.

125 Having thus described my invention, what I claim as new and useful and desire to secure by Letters Patent is:

1. In a timer having distributing rings 125 and a breaker mechanism, a rotatable shaft, a sleeve longitudinally slotted at one end mounted on the shaft, said sleeve carrying ring engaging contacts, another sleeve having a breaker actuating cam fitted over the 130

shaft and extended over the slotted end of the first named sleeve, said cam sleeve having an end slot to aline with the slot in the other sleeve, a pin removably fitted into the shaft and projecting into both slots, and means on the shaft beyond the cam sleeve for holding the latter against the first named sleeve.

2. In a timer having distributing rings 10 and a breaker mechanism, a rotatable shaft, a sleeve longitudinally slotted at one end mounted on the shaft, said sleeve carrying ring engaging contacts, another sleeve having a breaker actuating cam fitted over the shaft and extended over the slotted end of the first named sleeve, said cam sleeve having an end slot to aline with the slot in the other sleeve, and narrower than said other

slot, a pin removably fitted into the shaft and projecting through the slots, said pin 20 having an enlarged portion fitting the wider slot, and a nut on the shaft beyond the cam sleeve and impinging against the latter.

3. In a timer, a breaker mechanism mounted therein adjacent the outer face 25 thereof, a cover turnably mounted over said mechanism and partly cut away to expose the same, a removable cover-segment adapted to fit the cut away portion of the main cover and turnable therewith, and clip 30 means between the segment and cover to enable the cover to be turned to any position without the segment falling from place.

In testimony whereof I affix my signature.

PAUL E. DEMMER.
